UNITED STATES PATENT OFFICE.

ARTHUR HADDOCK, OF EAST ORANGE, NEW JERSEY, ASSIGNOR TO WESTERN ELECTRIC COMPANY, INCORPORATED, OF NEW YORK, N. Y., A CORPORATION OF NEW YORK.

CONTACT TERMINAL.

Application filed September 20, 1921. Serial No. 501,984.

To all whom it may concern:

Be it known that I, ARTHUR HADDOCK, a citizen of the United States, residing at East Orange, in the county of Essex, State of New Jersey, have invented certain new and useful Improvements in Contact Terminals, of which the following is a full, clear, concise, and exact description.

This invention relates to contact terminals and particularly to contact terminals adapted for use on multiple contact electrical apparatus such as dial switches, rheostats, and the like.

The object of the invention is the provision of an improved contact terminal which may be economically manufactured and which may be secured to a mounting plate without the use of additional parts such as screws or rivets.

A further object is the provision on such a terminal of suitable means for supporting conductors or resistance elements.

In accordance with the above objects, the preferred form of the invention comprises a flat, punched metal contact terminal adapted to be mounted edgewise, provided with a pair of integral lugs whereby it may be secured to a mounting plate, and a hook-shaped end portion to which a conductor may be readily secured.

The invention will be better understood from a detailed description with reference to the accompanying drawing, in which Fig. 1 is a perspective view of a dial switch, and Fig. 2 is a perspective view of a contact terminal in accordance with the present invention.

In Fig. 1 the terminals 1 are shown arranged in a circular row mounted on a plate of insulating material 2. A movable contact 3 is attached to a handle 4 by which it may be rotated to wipe over the contact terminals.

As shown in Fig. 2, the contact terminal comprises a main body portion 1' having a contacting surface 1² on one edge. Two parallel lugs 1³ and 1⁴ extend from the edge of the main portion opposite the contacting surface 1². A hook-shaped soldering terminal 1⁵ is also provided whereby conducting wires may be attached as illustrated in Fig. 1.

As will be seen from an examination of Fig. 1, the two lugs 1³ and 1⁴ extend through

apertures in plate 2 and the lug 1⁴ is staked over at its end after assembly.

The terminal may be punched from a piece of thin flat metal, thus permitting a large number to be used in a relatively small space. It requires no bending operation and no screws or rivets to hold it in place.

The appended claims are not to be construed as limited to the specific showing as there are many possible modifications of the design which would come within the scope of the invention.

What is claimed is:

1. In combination, a perforated mounting plate, a metal contact, and a plurality of lugs projecting from said contact, said contact being secured to said plate solely by means of one of said lugs whose end projects through a perforation in said mounting plate and is distorted.

2. In combination, a perforated mounting plate, a metal contact, a soldering terminal, and a plurality of lugs projecting from said contact, said contact being secured to said mounting plate solely by means of one of said lugs whose end projects through a perforation in said mounting plate and is distorted.

3. In combination, a perforated mounting plate, a flat punched metal contact, and a plurality of lugs projecting from one edge of said contact, said contact being secured to said plate solely by means of one of said lugs whose end projects through a perforation in said mounting plate and is distorted.

4. In combination, a perforated mounting plate, a flat punched metal contact, a soldering terminal, and a plurality of lugs projecting from one edge of said contact, said contact being secured to said plate solely by means of one of said lugs whose end projects through a perforation in said mounting plate and is distorted.

5. In a switching device, a perforated mounting plate, a punched metal contact, a plurality of lugs integral with said contact, said contact being secured to said plate, solely by means of one of said lugs whose end projects through a perforation in said mounting plate and is distorted, and a soldering terminal integral with said contact and extending away from the edge of said mounting plate.

6. In combination, an insulating mount-

- ing plate having perforations, a plurality of flat metal contacts, each having lugs projecting from one edge for registering with said perforations, the edges of said contacts 5 from which the lugs project forming a bearing surface for said contacts, said contacts being secured to said mounting plate solely by one of said lugs whose end projects through said mounting plate and is upset.
- 10 7. In combination, an insulating mounting plate having perforations, a plurality of flat metal contacts, each having lugs projecting from one edge for registering with said perforations, the edges of said contacts 15 from which the lugs project forming a bearing surface for said contacts, a soldering terminal integral with each contact and extending away from the edge of said mounting plate, said contacts being secured to said mounting plate solely by one of said lugs whose end projects through said mounting plate and is upset.
8. In combination, an insulating mounting plate having rows of closely spaced perforations therein, a plurality of flat punched metal contacts, each having lugs projecting from one edge and registering radially with said perforations, the edges of said contacts from which the lugs project bearing upon said mounting plate, said contacts being secured to said mounting plate solely by one of said lugs whose end projects through said mounting plate and is upset.
- 30 In witness whereof, I hereunto subscribe my name this 17th day of September A. D., 35 1921.

ARTHUR HADDOCK.
